UNITED STATES PATENT OFFICE.

JAMES T. HOYT, OF NEW YORK, N. Y.

CABINET FOR PAPER AND OTHER MATERIALS.

SPECIFICATION forming part of Letters Patent No. 369,642, dated September 6, 1887.

Application filed January 6, 1887. Serial No. 223,577. (No model.)

To all whom it may concern.

Be it known that I, JAMES T. HOYT, a citizen of the United States, residing at New York, in the county and State of New York, have invented new and useful Improvements in Cabinets for Paper and other Materials, of which the following is a specification.

This invention relates to a cabinet or case for paper and other materials, as set forth in the following specification and claims, and illustrated in the accompanying drawings, in which—

Figure 1 is a section in the plane yy , Fig. 2. Fig. 2 is a front view, partly in section, in the plane xx , Fig. 1.

Similar letters indicate corresponding parts. The case is made of metal or other suitable material, and consists of a base, A, and a front, C. By having a cover, B, suitably hinged or applied, ready access can be had to the interior of the case, while at the same time the interior of the case can be protected. Attaching devices—such, for example, as eyes D—enable the case to be secured in a convenient place. In the drawings is shown a package, E, consisting of sheets of sanitary paper placed within the cabinet. A suitable attaching device, F, holds the package E in place in the cabinet.

30 A simple form of attaching device F is shown in the drawings, where the attaching device is represented as consisting of a prong or arm passing through the sheets E, and bent over against the sheets E, as seen at F in Fig. 2.

35 By providing the arm F with a hook or equivalent device, G, the arm F can be secured to the cabinet, while at the same time the arm F can be readily removed from the cabinet when said arm is to be provided with a fresh supply of sheets E, or when said arm is to be repaired or replaced by another arm or attaching device.

In the case or cabinet are mounted rollers M O. The rollers M O are connected, so as to 45 revolve together. In the drawings said rollers are shown as being connected by pulleys R S, and by a cord or chain, Q. Of course other well-known devices—such, for example, as gear-wheels—can be used to connect the 50 rollers M O. By providing one of the rollers with a suitably-applied handle or finger-but-

ton, P, the rollers can be actuated from the exterior of the cabinet, the actuation of one roller, as already noted, imparting motion to the other roller. The sheets E are pressed 55 against the rollers M O by a suitably-applied base, H. A spring, I, forces the base H in the proper direction to press the sheets E against the rollers M O. By moving or revolving the rollers M O in the proper direction that one of the sheets E lying next to the rollers M O will be moved toward the outlet or exit opening N of the cabinet. When said sheet has passed some distance out through the opening N, said sheet can be grasped by 60 the hand and drawn completely out of the cabinet. Such drawing out of said sheet imparts motion to the rollers M O. As the inner end of said sheet passes out of contact with the roller M, said roller M comes into 65 contact with the next succeeding sheet of the package E. The first-named sheet, continuing to pass out of the cabinet, will cause revolution of the roller O, and consequently of the roller M, even after said first-named sheet has passed 70 out of contact with the roller M, but while said first-named sheet still remains in contact with the roller O. Such revolution of the roller M causes the next succeeding sheet of the package E to travel toward the opening N a sufficient 75 distance, so that when the first-named sheet has passed completely out of the cabinet the next succeeding sheet has advanced sufficiently far out through the opening N to enable such next succeeding sheet to be grasped 80 by the hand and withdrawn from the cabinet. Sheet after sheet can thus be rapidly drawn out of the cabinet without its being necessary to actuate the handle P every time it is required to start a sheet moving out of the cabinet. 85

By providing the rollers M O with corrugations or roughened surfaces or with elastic material—such, for example, as india-rubber—the rollers M O will secure a sufficient grip 95 upon or friction against the sheets E to move each sheet coming into contact with the rollers M O toward the exit-opening N.

The base H is moved by the spring I toward the rollers M O as the package E decreases in 100 thickness in consequence of the withdrawal of sheets. The rollers M O can thus always engage

one sheet resting upon the base H. Said base H is provided with arms J, moving in slots or ways L in the cabinet. Said arms J are provided with screw-threads for the reception of nuts K. When a fresh package E is to be inserted into the cabinet, the base H is moved away from the rollers M O, and fixed in such position away from the rollers M O by screwing up or tightening the nuts K. The nuts or clamping devices K conveniently serve as handles for moving the base H away from the rollers M O. When the base H is secured at a distance from the rollers M O, a package E can be readily inserted into the cabinet and placed upon or over the base H. The nuts K are then loosened, when the spring I, acting upon the base, moves said base, so that the package E is carried against the rollers M O.

The cabinet can be conveniently used for such material, for example, as sanitary paper, or in barber-shops to hold shaving-paper, or for holding other material—such, for example, as labels or wrapping-paper.

It must be remarked that this invention is an improvement on the cabinet described in my Patent No. 333,073, dated December 22, 1885, and that by the additional feed-roller, M, certain advantages are gained, as fully pointed out in the foregoing specification.

Heretofore a ticket-case has been composed of a receptacle for the tickets, having a front opening for their withdrawal singly, the bottom of the receptacle containing three pin or friction wheels geared together, all in such manner that on starting the apparatus the bottom ticket is placed half-way out. To withdraw a ticket, the bottom one is drawn out and by its outward movement rotates the front pin or friction wheel, and thereby rotates the other

two wheels, the pins or surfaces of which engage with the underside of the second ticket, so that the same is partially pushed out to repeat the operation. This, however, is not my invention, and is not claimed by me.

What I claim as new, and desire to secure by Letters Patent, is—

1. The combination, with a case or cabinet having an exit-opening, N, an attaching device, F, for holding a package of sheets of paper, and a spring-impelled base, H, for pressing the package forward, of two feed-rollers, M and O, connected to rotate in unison against the front of the package, substantially as described.

2. The combination, with the cabinet or case A, having the slots L, and a roller to press against the package of sheets of paper, of a spring-impelled base, H, having at each end an arm, J, extending through and slidably along the slots in the cabinet or case, and clamps K, applied to said arms, for holding the base in the rear of the cabinet, substantially as described.

3. The combination, with a case or cabinet provided with an exit-opening, N, and with a spring-impelled base provided with nuts or clamping devices K, of a guide slot or way, L, for said base, rollers M O, and mechanism, substantially as described, for connecting said rollers M O.

In testimony whereof I have hereunto set my hand and seal in the presence of two subscribing witnesses.

JAMES T. HOYT. [L. S.]
